WATER CLOSET

David S. Williams, Portland, Oreg.

Application August 29, 1935, Serial No. 38,413

8 Claims. (Cl. 4-249)

This invention relates to water closets of the siphon jet or any other type, which have associated therewith tripping mechanism adapted for actuation by foot pressure for flushing the interior of the bowl when desired.

An equally important object of the invention is to provide a water closet having a base which may be held securely against a floor without exposing to view the anchoring means and presenting, as a result thereof, a neat and sanitary appearance.

A further object of the invention is to provide a water closet having a ledge rearwardly extending therefrom, adapted for supporting the flushing means, such as a flush valve or a pressure tank.

Still another object of the invention is to provide a water closet having associated therewith a saddle seat which is opened in front and in back and which is hinged with respect to the ledge in such manner that very little of the hinging means is exposed to view, thus assuring sanitary conditions at locations of vital importance.

The primary object of my invention is to provide a water closet which is uniquely designed in order that it may have combined therewith tripping mechanism for either the flush valve or pressure tank capable of manipulation by foot pressure rather than by the use of one's hands.

As a corollary to the previous object, the invention provides within the framework of the base of the water closet a pair of flanges or ledges, each one of which is capable of retaining therein a portion of the tripping mechanism used for flushing the interior of the bowl when desired.

Another object of the invention is to provide a water closet neat and ornamental in appearance, sturdy and simple in construction and capable of being maintained in a sanitary condition with a minimum of effort.

Other objects and advantages will become apparent and readily understood from the following description which is to be considered in conjunction with the accompanying drawing forming a part hereof which, of necessity, is merely illustrative of the principles of the invention and in which:

Figure 1 is a side elevation of a water closet embodying the principles of my invention.

Figure 2 is a front elevation of the water closet shown in Figure 1.

Figure 3 is a fragmentary top view, partially in section, of the water closet shown in Figures 1 and 2 illustrating the construction of the seat

and the manner of connecting the seat to the closet bowl.

Figure 4 is a fragmentary, sectional, end view, taken on line 4-4 of Figure 1, looking in the direction indicated, illustrating the position the water closet embodying the principles of my invention assumes upon a supporting surface and when connected to a disposal pipe.

Figure 5 is a fragmentary, sectional, side view, taken on line 5-5 of Figure 2, looking in the direction indicated, graphically showing the arrangement of the shaft and related members of the tripping mechanism with respect to the water closet.

Figure 6 is a fragmentary, end view, taken on line 6-6 of Figure 5, looking in the direction indicated, showing the arm connected to the shaft with a plurality of openings therein for adjustment.

Figure 7 is a top view of an anchoring flange, taken on line 7-7 of Figure 5, looking in the direction indicated.

Figure 8 is a side elevation of a water closet embodying the principles of my invention but applied to a flush tank.

Figure 9 is a perspective of the anchor foot used in anchoring the front portion of the water closet fixedly secured to the supporting surface.

Reference character A designates a water closet containing some of the conventional contours incorporated in a water closet of the siphon jet or other type, but many of the old elements have been modified, and many additional elements have been incorporated, a description of which will follow forthwith. The water closet designated by reference character A has a bowl 1. Rim 2 is flanged and provides a supporting surface for the seat 3. Lip 4 is formed at the front end of the bowl 1, and a shelf 5, offset from rim 2, as shown at 6, extends rearwardly in parallel alignment with the rim. Bowl 1 possesses a vertical front 7, and the conventional contours at its rear, as shown at 8. The base 9 has parallel ledges 10 and 11 disposed at each side thereof. These ledges extend throughout the length of the base. Ledge 10 has an opening 12 at its front end and an opening 13 at its rear, each aligned with the other. Ledge 11 also has similar openings 14 (not shown) and 15.

A bushing 16 is secured within opening 12, and a similar bushing 17 is secured within opening 13. In this manner, journal bearings are formed for shaft 18 which is movably disposed through bushings 16 and 17. Foot pedal 19 is locked to the front end 20 of shaft 18 and held secured there-

to in any well known manner, as by threaded screw 21. Arm 22 is locked against the rear end 23 of shaft 18 and held secured thereto by any well known means, as by threaded screw 24. The arm 22 has a plurality of openings 25.

Stationed upon or in any other way associated with shelf 5 is a flushing valve 26 of any well known type which has tripping handle 27 extending therefrom. Link 28 has a yoke 29 at one end and a similar yoke 30 at the other end. Yoke 29 is joined to tripping handle 27, and yoke 30 may be joined to arm 22 at one of the openings 25 disposed within arm 22. It at once becomes clear that, upon the application of downward pressure on the foot pedal, pressure is applied to the tripping handle 27 through the link connection therebetween.

To retain the water closet in secured position against the floor without exposing to view any of the anchoring means, there is provided an anchoring flange 31 which has openings 32 therethrough. This flange is secured to the floor 33 in any well known manner, as by threaded screws 34 passing through openings 32. The front portion of base 8 has a ledge 35 with an inclined surface extending inwardly. Anchoring foot 36, which is composed of a single member, having a flat surface, as at 37, and an inclined surface, as at 38, is positioned against the inclined surface of ledge 35 and retained securely thereagainst in any well known manner, as by screws 39 being inserted through openings 40 formed within flat surface 37. In this manner, the front end of the water closet is anchored without exposing any of the anchoring means. The rear end of the water closet is anchored by the insertion, through openings provided within the base 8 out of the line of sight, of a plurality of bolts 42 which are threadably secured within openings 43 formed within anchoring flange 31. In this manner, not only is the water closet anchored securely to the floor 33 and the anchoring means hidden from normal view, but nothing interferes with the movement of the shaft 18.

The joinder between disposal outlet 44 of the water closet with the disposal conduit 45 is accomplished in the well known manner, such as by the use of putty or other adhesive substance.

An additional improvement to be found in my invention is illustrated graphically in Figure 3 wherein there is shown a saddle seat 3 having an open back, as shown at 46, and an open front, as shown at 47, thus forming two supports 48 and 49. Support 48 has a socket member 50 extending rearwardly therefrom and support 49 has a similar socket member 51 extending rearwardly therefrom. Passing through transversely of the shelf 5 is a shaft 52 which is journaled in bushings 53 and 54 extending through openings formed within said shelf. Socket 50 is locked to end 55 of shaft 52, and socket 51 is locked to the other end of shaft 52 in such a manner that, if one support is lifted, the other also will be lifted. It will be seen that, by this construction, very little of the hinging member is exposed to view; and, further, the seat 3 is substantially in the same plane as the shelf 5, giving neatness of appearance to the water closet and facilitating the maintenance of the water closet in a sanitary condition. As a further aid to sanitation, and by way of giving added beauty to the whole apparatus, a cover 56 is placed around the flush valve 26 and tripping handle 27 and is supported upon shelf 5. It should be noted that the link

28 is so positioned as to be out of view from the front of the water closet.

There is shown in Figure 6 a water closet embodying the identical construction heretofore described, except that, on shelf 5, is disposed a flush tank 57 having cover 58 thereon. Flush tank 57 has a tripping handle 59 extending rearwardly therefrom to which a link 60 of a slightly modified shape from that of link 28 is secured. Thus, it will be seen that the principles of the invention may be applied either to a flush valve or a flush tank without materially deviating from the objects of the invention.

Attention might well be called at this time to the fact that ledge 11, as heretofore stated, has openings similar to that of ledge 10. The purpose of duplicating the openings is to permit the placing of the tripping mechanism on the left side of the closet bowl where it is found necessary during the installation of the water closet to make such an alteration. When not in use, the openings 14 (not shown) and 15 are covered by any well known means, as by a button 61.

While this specification sets forth the present type of construction, still in practice, deviations in detail may be resorted to by those skilled in the art, but which do not depart from the spirit of the invention as claimed in the appended claims, I therefore reserve to myself all such modifications and adaptations as fall within the scope of the invention as defined in the claims.

I claim:

1. In apparatus of the class described, a toilet bowl of conventional contour having a base and a front portion, a pair of ledges extending one on each side of the base and made integral therewith, at least one of said ledges having a pair of openings formed in alignment with each other, a support extending rearwardly from the toilet bowl and made integral therewith, flushing means associated with said support, and means joined to said flushing means and passing through the openings in one of said ledges adapted for tripping said flushing means by the application of foot pressure upon said means. 45

2. In apparatus of the class described, a toilet bowl of conventional design having a base and a front portion, a ledge formed on each side of and made integral with the base, said ledges having each a pair of openings formed in alignment with each other, a shelf extending rearwardly from and in offset relationship to the toilet bowl, a shaft passing through and disposed transversely of said shelf, seat sections locked against the ends of said shaft, flushing means associated with said shelf, and means joined to said flushing means and passing through the openings in one of said ledges adapted for tripping said flushing means by the application of foot pressure upon said means. 60

3. In apparatus of the class described, a toilet bowl having a base and a front portion, a pair of ledges extending outwardly from the base, a pair of openings formed in each ledge in alignment with each other, a shelf extending rearwardly from and in offset relationship to the toilet bowl, a shaft passing through and disposed transversely of said shelf, seat sections locked against the ends of said shaft, flushing means associated with said shelf, means joined to said flushing means and passing through the openings in one of said ledges adapted for tripping said flushing means by the application of foot pressure thereupon, and means associated with the base of the toilet bowl for anchoring said base against the floor. 70 75

4. In apparatus of the class described, a toilet bowl having a base and front portion of conventional design, a pair of ledges extending in parallel relationship from the base and made integral therewith, a pair of openings formed in each ledge in alignment with each other, a shelf extending rearwardly from the top of the toilet bowl, flushing means associated with said shelf, a shaft disposed through the openings in one of the ledges, a foot pedal locked to the front end of said shaft and means joined to the other end of said shaft and to the flushing means adapted for actuating the flushing means by the application of downward pressure upon the foot pedal.
5. In apparatus of the class described, a toilet bowl having a base and a front portion, a pair of ledges extending from and made integral with the base, a pair of openings formed in each ledge, a shelf extending rearwardly from the toilet bowl, flushing means associated with said shelf, a shaft movably disposed through the openings in one of the ledges, a foot pedal locked to the front end of said shaft, an arm locked to the other end of said shaft, and a link joined to the flushing means and adjustably joined to the arm, thereby permitting the transmittal of any downward pressure applied upon the said pedal to the said flushing means.
6. Tripping mechanism to be used with a toilet bowl and flushing means of the class described comprising, a shaft passing through the base of said toilet bowl, a pedal locked to the front end of said shaft, an arm locked to the other end of said shaft and a link joining the said arm to the said flushing means, whereby, upon the application of downward pressure upon the pedal, the flushing means will be actuated to flush the interior of the toilet bowl.
7. Tripping mechanism to be used with a toilet bowl and flushing means of the class described comprising, a shaft passing through the base of said toilet bowl, foot actuated means locked to the front end of said shaft, an arm locked to the other end of said shaft and means joined to said arm and to the flushing means whereby, upon the application of downward pressure upon the foot actuated means, the flushing means will be actuated.
8. Tripping mechanism to be used with a toilet bowl of conventional design and flushing means of conventional design associated therewith comprising, a shaft passing through the base of said toilet bowl, foot actuated means locked to the front end of said shaft and means secured to the other end of said shaft and to the flushing means adapted for actuating the flushing means by the application of downward pressure upon the foot actuated means.
